[57] CLAIM

The ornamental design for a pedal for racing bicycle, as
shown and described.

DESCRIPTION

FIG. 1 is a perspective view of a pedal for racing bicycle showing my new design;

FIG. 2 is a front elevational view thereof, it being understood that the rear is a mirror image of the front shown herein;

FIG. 3 is a top plan view thereof;

FIG. 4 is a bottom plan view thereof; and

FIG. 5 is a left side elevational view thereof, the right side being a mirror image of that shown.

FIG. 1

FIG.3

FIG.5

FIG.2
